UNITED STATES PATENT OFFICE.

AUGUST W. KURZ, OF CLEVELAND, OHIO.

VAULT-HEAD.

No. 921,123.

Specification of Letters Patent.

Patented May 11, 1909.

Application filed March 28, 1904. Serial No. 200,258.

To all whom it may concern:

Be it known that I, AUGUST W. KURZ, a citizen of the United States, and a resident of Cleveland, in the county of Cuyahoga and 5 State of Ohio, have invented certain new and useful Improvements in Vault-Heads, which improvements are fully set forth in the following specification.

This invention relates to improvements in 10 structures of that class employed in connection with subterranean vaults, the same serving to control, each the entrance to the vault with which it is conjoined, and being commonly known as "vault heads."

15 The objects of this invention are to provide a structure of the character indicated, which shall be simple and inexpensive as regards construction; durable, efficient and reliable in practical service; which shall embody elements relatively adjustable to suit 20 conditions involved in the installation of the completed structure for service, together with elements whereby are secured important results in connection with the displacementable lid made use of, particularly its application to, and displacement from, the main member of the construction; which shall be 25 attractive in appearance; and which shall possess certain well-defined advantages over 30 prior analogous structures.

The invention consists in the novel disposition and relative arrangement of the various coöperating parts thereof, whereby the attainment of the above objects are 35 rendered practicable; in certain combinations; and in certain details of construction, all of which will be specifically referred to hereinafter and set forth in the appended claims.

40 The invention is clearly illustrated in the accompanying drawings, wherein similar reference-numerals denote corresponding parts throughout the several views, and as to said drawings:

45 Figure 1 is a plan view of a vault head embodying my said improvements, the lid made use of occupying its normal position. Fig. 2 is a vertical section taken along the angular line *a*—*a* of Fig. 1, the lid aforesaid being 50 shown as having been fully displaced from its normal position. Fig. 3 is a perspective view showing one of the novel separators availed of, detached from the general construction, the scale being enlarged.

55 In a general sense my present invention comprises a main member; a hood conjoined

therewith; and a tongued separator, the latter being interposed between said hood and said member, and its tongue serving to facilitate the assembling of the respective 60 aforesaid parts for service.

It further comprises a main member forming a manhole; a lid for normally spanning said manhole, said lid being linked to said member, interiorly thereof, for a displacing movement mainly in a horizontal plane; and means for limiting the horizontal displacing movement of said lid to one direction only.

It still further comprises a main member 70 forming a manhole, and a lid, the latter normally spanning said manhole, and being linked to said member, interiorly thereof, for a displacing movement in a plurality of varying planes.

Having reference to the accompanying drawings, 2 denotes the main member forming the manhole for the general construction, as in common practice; 3 the hood availed of for spanning a portion of said manhole; 80 and 4 the lid made use of for normally spanning the remaining portion of said manhole, the said lid approximating the form of a grate or otherwise, as conditions may warrant.

85 The hood 3 has a depending lip 5, offset inwardly at its juncture with said hood, and thereby forming for the latter an exterior shoulder 6, co-extensive with the rear portion and opposite sides of said hood.

90 7 denotes a separator, interposed between the shoulder 6 and the adjacent edge of the member 2, said separator having a tongue 8 depending therefrom.

95 9 is a fastening bolt, which projects through the lip 5, adjacent wall of the member 2, and the tongue 8, to receive a nut 2', the relative arrangement of said tongue with respect to said separator being such that, when said separator is in place, the tongue 8 lies along 100 the outer surface of said wall of the member 2.

105 Under the foregoing disposition of the parts, the member 2 at all times presents non-angular supporting resistance to the hood 3, or, in other words, a direct supporting resistance in contradistinction to that resistance which the member 2 presents to the hood 3 where the bolt 9, arranged at right angles to the wall aforesaid of the member 110 2, becomes a factor in the presentation of such supporting resistance.

It will be understood that the dimensions of the separator 7 may be materially varied, and that the vertical adjustment of the hood 3 with respect to the member 2, may be varied accordingly. It will be further understood that a plurality of separators such as herein described, may be employed when necessary or desirable.

To permit the above-named adjustment of the hood 3, the opening 3', in the lip 5, through which the bolt 9 passes, should be vertically elongated, substantially as shown in the drawings.

The member 2 is provided, interiorly thereof, with a projection or web 4', and therewith the link 5' has a limited sliding engagement, said link being conjoined with, and depending from, the lid 4.

By preference the link 5' has the form of a rod, and penetrates the projection 4' by way of a suitable opening 6' formed therein.

A stop 7' is firmly conjoined with the link 5', below the projection 4', said stop accordingly serving to prevent the disengagement of said link upwardly from said projection.

Under normal conditions the lid 4 rests on ledges, (one of which is clearly indicated in Fig. 2 of the drawings, and denoted by the reference-numeral 8'), arranged interiorly of the member 2, at the opposite sides thereof, each of said ledges being somewhat downwardly removed from the upper edge of the wall of the member 2 along which it runs, as in common practice. Accordingly the lid 4 must necessarily undergo an initial displacing movement somewhat upwardly, in order to clear the walls of the member 2 for a final displacing movement in a substantially horizontal plane, the axis of which final displacing movement is determined by the link 5', and the latter, in this instance rotating in the web or projection 4' and moving with the lid 4 when such lid is thus horizontally moved; and to permit the foregoing initial displacement of the lid 4, the distance in the clear between said lid, and the stop 7' along said link, should be equal to, or greater than, the combined thickness of said projection and the height of the vertical wall of member 2 above the projection or web 4'.

If, however, it is desired to limit the motion of the lid to an upward radial motion in a vertical plane the said distance between the point of connection of said link with said lid and the point of location of stop 7' along said link may be less than that before stated. If the said distance described is thus reduced the lid then may be only lifted at its free end, the end loosely secured to the manhole remaining on and turning on the lid seat immediately thereunder. Obviously two links may be used in this case one at each corner of the same end of lid or if one link is used it is then preferably located at the middle of the side which is loosely secured to the manhole to prevent twisting off.

Stop 7' may take the form of a collar, permanently held in place by means of a nut 9', the link 5' being suitably reduced and threaded to receive these parts, and being swaged or expanded at its end to insure permanency in the disposition of such parts.

In order to prevent the lid 4, when it is being replaced, from going beyond the manhole opening, I provide means for limiting its horizontal movement in a direction toward the hood, beyond a certain point, such means consisting of a suitable stop 2'', which blocks the lid 4, when brought to its proper position to descend into engagement with its supporting ledges aforesaid, against horizontal movement in the opposite direction. The stop 2'' is here shown as constituting a part of the hood 3, and a co-operative relation is accordingly established between said hood and the lid 4, which members of the general construction are respectively shown as serving, the one to permanently span a portion of the manhole aforesaid, and the other to displaceably span the remaining portion of said manhole, and being limited to a displacing movement therefrom in one direction only along a horizontal plane, by said hood.

The link 5' may be conjoined with the lid 4 in any appropriate manner; but to insure a displacing movement of said lid along a plurality of varying planes, said link should be loosely conjoined with said lid, as through the medium of a pivot or pintle 3''.

To facilitate the adjustment of the hood 3 with respect to the member 2, I form integrally two or more of the separators 7, each differing in spacing width from the other or others, and each having a tongue 8, thereby providing a multiple, tongued separator well calculated to present in a single construction a plurality or series of spacing widths for varying the adjustment of the hood 3 with reference to the member 2.

Where single tongued separators of varying spacing width (such as first herein described), are employed in the adjustment of the hood 3 with respect to the member 2, some of a given spacing width are liable to be interchanged for others of a different spacing width, or be lost in transit or otherwise, thereby causing delay and inconvenience in the work of installing the construction as a whole; and such objectionable contingencies are well overcome by the multiple, tongued separator above described.

When the separator is used with the tongues as described and illustrated the same affords but two spacing widths. Manifestly, however, two additional spacing widths may be made use of in said separator if desired by placing the one or the other of the tongues along its greatest dimension in a vertical position with its flat side preferably against the depending lip of the hood, in which case it will, obviously, however, require that the

separator be secured in some manner to the hood and that the hood be secured separately to the main member.

The operation of the construction will be apparent from the foregoing description thereof.

It will be seen that my present invention is particularly well adapted to conserve the purposes for which it is intended, and further 10 that the same may be modified to some extent without materially departing from the spirit and principle thereof.

Having thus described my invention what I claim and desire to secure by Letters-Pat- 15 ent, is:

1. In a vault head, the combination with a main member forming a manhole, and a hood permanently spanning a portion of said manhole; of a lid for normally spanning the 20 remaining portion of said man-hole, said lid being loosely conjoined with said member, interiorly thereof, for a rotary displacing movement in a horizontal plane, and said hood projecting above the upper edges of the 25 main member and forming a stop to limit the rotary movement of the lid toward the hood when the latter is replaced, substantially as described.

2. In a vault head, the combination with a 30 main member forming a manhole, and a hood crossing said manhole transversely and permanently spanning a portion thereof, of a lid for normally spanning the remaining portion 35 of said manhole, said lid being permanently joined to said member interiorly thereof by a loose connection at one of the sides or corners of the lid for a rotary displacing movement in a horizontal plane, the said hood projecting above the top of the main member to 40 form a stop to limit the rotary movement of said lid beyond the hood when the lid is being replaced, substantially as described.

3. A vault head comprising a main member forming a manhole, a lid for normally 45 spanning said man hole, and a link connecting the lid and the main member, the said link being so connected to the main member that it is free to move relatively thereto but not become detached therefrom, and so connected to the lid, that the lid has a movement 50 relative to the link without detachment therefrom, whereby the lid is allowed a free displacing movement in a number of planes, substantially as described.

55 4. A vault head comprising a main member forming a manhole and having an interior projection; a lid for normally spanning said manhole; and a link loosely conjoined with said lid, the said link loosely connecting 60 said lid with the projection aforesaid, for a displacing movement on the part of said lid in a horizontal plane or in a plurality of radial vertical planes, substantially as herein specified.

65 5. A vault head comprising a main mem-

ber forming a manhole and having an interior projection provided with an opening; a lid for normally spanning said manhole; and a rod-like link, the latter penetrating said projection by way of the opening therein, being suitably conjoined with said lid for an upward radial movement in a vertical plane, and having a permanent stop arranged therealong, below said projection, substantially as herein specified.

6. A vault head comprising a main member forming a manhole and having an interior projection provided with an opening; a lid for normally spanning said manhole; and a rod-like link, the latter penetrating 70 said projection by way of the opening therein, being suitably conjoined with said lid for a combined upward radial movement in a vertical plane and a rotary movement in a horizontal plane, the said link having a permanent stop arranged therealong below the 75 said projection, substantially as described.

7. A vault head comprising a main member forming a manhole and having an interior projection provided with an opening; a lid for normally spanning said manhole; and a rod-like link, the latter penetrating 80 said projection by way of the opening therein, being loosely conjoined with said lid, and having a stop arranged therealong, below 85 said projection, substantially as herein specified.

8. A vault head comprising a main member forming a manhole and having an interior projection provided with an opening; a lid for normally spanning said manhole; and a link, the latter penetrating 90 said projection by way of the opening therein, being pivotally conjoined with said lid, and having a collar arranged therealong, below said projection, the said collar being held permanently 95 in place by a nut, substantially as herein specified.

9. A vault head comprising a main member forming a manhole; a hood for normally 100 spanning a portion of said manhole, the said hood having a depending lip taking into said member; a tongued separator, interposed between said hood and said member; and means for applying a clamping force to the 105 lip of said hood and the tongue of said separator, the wall of said member lying between said lip and said tongue, substantially as herein specified.

10. A vault head comprising a main member forming a manhole; a hood normally 110 spanning a portion of said manhole, said hood having a depending lip taking into said member; a tongued separator, interposed between said hood and said member; a 115 headed fastening bolt, the latter projecting through the lip of said hood, through the adjacent wall of said member, and through the tongue of said separator; and a nut on said bolt, and whereby a clamping force may 120

be applied to said lip and said tongue, the wall of said member lying between them, substantially as herein specified.

11. A vault head comprising a main member forming a manhole; a hood normally spanning a portion of said manhole, said hood having a depending lip taking into said member, and provided with a vertically elongated opening; a tongued separator interposed between said hood and said member; a headed fastening bolt, the latter projecting through the lip of said hood by way of the opening aforesigned therein, through the adjacent wall of said member, and through the tongue of said separator; and a nut on said bolt, whereby a clamping force may be applied to said lip and said tongue, the wall of said member lying between them, substantially as herein specified.

12. For a vault head comprising a main member and a hood, a multiple separator for insertion between said hood and member, the said separator embodying a plurality of different spacing widths, and a plurality of tongues projecting therefrom, substantially as herein specified.

13. For a vault head comprising a main member and a hood, a multiple separator for insertion between said hood and said member, the said separator embodying a series of different spacing widths, substantially as described.

14. In a vault head, a lid having a link at all times pivotally attached thereto, the said link being in turn at all times directly conjoined with the vault head by a loose connection so as to permit the lid being raised to an inclined or vertical position, substantially as described.

15. A vault head comprising a main member formed with an opening therein, a non-circular lid adapted to close said opening, means for loosely connecting the lid to the main member, said means permitting the lid to be raised above the main member and then rotated to uncover the opening and being of such length that it will prevent the lid from being dropped through the opening in the main member.

16. A vault head comprising a main member formed with an opening therein, an upstanding flange around a portion of said opening, a lid adapted to fit within said upstanding flange, means for loosely connecting the lid to the main member, said means being of such length that the lid may be lifted above the flange and rotated.

17. A vault head comprising a main member formed with an opening therein, a lid for closing said opening, a link for loosely connecting the lid to the main member, said link being permanently and flexibly connected to said lid and of such length as to permit the lid to be bodily lifted a predetermined distance, and being so connected with the lid as to permit said lid to be swung laterally on said link, and a stop on the lower end of said link to prevent the upward withdrawal of the link from the main member.

18. A vault head comprising a main member formed with an opening therein, an upstanding flange around a portion of said opening, a lid adapted to fit within said upstanding flange, and a device flexibly connected to the lid and freely movable through the main member for a limited distance, and a rigid stop on said device preventing the disconnection of the device from the main member but permitting the lid to be bodily lifted to free it from the upstanding flange, whereby said lid may be lifted above said flange and then swung laterally.

19. A vault head comprising a main member formed with an opening, a lid adapted to span said opening, a device loosely connecting the lid to the main member and adapted to permit said lid to be bodily lifted above the opening and to be then swung laterally therefrom, and a stop to prevent the withdrawal of the connecting device from the main member, whereby the lid may be bodily lifted and swung laterally, but cannot be dropped down through the opening in the main member.

AUGUST W. KURZ.
